UNITED STATES PATENT OFFICE.

CLIFFORD G. FISHER, OF PIQUA, OHIO.

CARRIAGE-CURTAIN WINDOW.

1,198,207.

Specification of Letters Patent. Patented Sept. 12, 1916.

Application filed April 1, 1916. Serial No. 88,266.

To all whom it may concern:

Be it known that I, CLIFFORD G. FISHER, a citizen of the United States, and a resident of Piqua, in the county of Miami and State of Ohio, have invented a new and Improved 5 Carriage-Curtain Window, of which the following is a full, clear, and exact description.

My invention relates to a frame for securing a window pane in a carriage curtain.

Objects of my invention are to provide a carriage curtain frame of the indicated class that will permit the pane to be readily slid into or out of place in the frame; to provide 15 an inner glass-receiving frame member at the inside of the curtain and an outer frame member having fastening tongues which are caused to penetrate the curtain and extend at the inner side thereof, the tongues being 20 flexible and adapted to be bent over the inner frame.

The invention will be more particularly described in the specific description following.

Reference is to be had to the accompanying drawings forming a part of this specification in which similar reference characters indicate corresponding parts in all the views.

Figure 1 is a front view of a carriage curtain window embodying my invention; Fig. 2 is a rear view thereof; Fig. 3 is a transverse section on the line 3—3, Fig. 2.

My improved window is adapted to be applied at an opening in the usual curtain material 10. The frame comprises a rectangular front frame section 11 and a rectangular inner or back section 12. The section 11 extends around the curtain opening at the 40 front while the rear section 12 extends around said opening at the back of the curtain.

The rear frame section 12 is channeled as at 12^a, the channel form extending at three 45 sides. The fourth side of the frame section 12 is open for the entrance and removal of the glass 13. The open side of the channeled back frame section may be at either end or at the top or bottom, but preferably, at an 50 end thereof whenever the position of the window makes it feasible to insert and withdraw the glass through an end opening. The open side of the frame in the present example is at an end of the frame as shown 55 at the right of Fig. 3, in which it will be seen the frame section 12 presents spaced in-

ner and outer members 12^b, between which the glass 13 is snugly accommodated to be entered in the top and bottom channels 12^a of the back frame section and directed to 60 the opposite end channel.

On the front frame section 11 are formed 65 tongues 14 at all sides of said frame section, and these tongues which are bendable, are forced rearwardly through the material of the curtain 10 and bent about the edge of 70 the back frame section and against the rear surface of the latter, as clearly shown in Figs. 2 and 3.

By the above described construction, those 75 fastening tongues 14 at the open side of the rear frame section serve the double function of fastening the rear frame section in position and of retaining the glass 13 against displacement.

All that is necessary to remove the glass 13 is to bend the tongues 14 at the open side away from the plane of the glass. Or, the complete frame may be removed from the curtain by bending the fastening tongues 14 80 at the several sides of the frame. I thus provide a frame which may be secured in position and the glass subsequently inserted, thereby minimizing the possibility of breaking the glass during the fastening of the 85 frame. Also the bearing of the fastening tongues is against frame parts and not directly against the glass.

The front frame section, in the present 90 example, is shown with transoms and mullions 11^a, and the back frame section with similar members 12^c.

Having thus described my invention, I claim as new, and desire to secure by Letters Patent:

1. In a carriage curtain window, a front frame section and a separate rear frame section, said rear frame section being in channeled form at three sides, the fourth side being open and presenting separated 100 inner and outer members, forming a passage for the entrance and removal of a window glass, the said front section having bendable tongues at the edges thereof to extend through the material of the curtain, 105 said tongues being bent around the edges of the rear frame section and against the back of the latter, those tongues at the open side of the frame extending across the 110 open side to retain the glass agains displacement.

2. A carriage curtain frame including a

front frame section, and a rear frame section in channeled form at two opposite sides, a third side of the rear frame section being open and presenting separated inner and outer members, forming a passage for the entrance and removal of a window glass, the said front section having bendable tongues at the edges thereof to extend through the material of the curtain, said 10 tongues being bent around the edges of the rear frame section and against the back of the latter, those tongues at the open side of the frame extending across the said open side to retain the glass against displacement.

15 3. In a carriage curtain window, a glass-holding frame in channeled form at three sides and open at the remaining side, and a device constituting both the means to secure said frame in the curtain and the means 20 to retain said glass in the frame, said device

consisting of a second frame member adapted to be placed at the opposite side of the curtain from the first frame, and resilient tongues on the inner side of the second frame and extending at the several sides 25 thereof, those tongues at the open side of the first frame extending across and closing the said open side, and engaging the said first frame at the outer side thereof, the tongues at the remaining sides of the second 30 frame extending over the outer side of the first frame.

In testimony whereof I have signed my name to this specification in the presence of two subscribing witnesses.

CLIFFORD G. FISHER.
